UNITED STATES PATENT OFFICE.

GEORGE G. NELSON, OF TURLOCK, CALIFORNIA.

BODY FOR DUMPING-TRUCKS.

1,373,628.

Specification of Letters Patent.

Patented Apr. 5, 1921.

Application filed November 24, 1919. Serial No. 340,363.

To all whom it may concern:

Be it known that I, GEORGE G. NELSON, a citizen of the United States, residing at Turlock, county of Stanislaus, State of California, have invented certain new and useful Improvements in Bodies for Dumping-Trucks; and I do declare the following to be a full, clear, and exact description of the same, reference being had to the accompanying drawings, and to the characters of reference marked thereon, which form a part of this application.

This invention relates to improvements in dumping trucks and vehicles of all kinds, being particularly adapted to be used in the transportation of rock, sand, cement and like products, which are adapted to be unloaded by dumping the same all at once.

I am aware of course that there are numerous dumping bodies and attachments, but as far as I know, they all leave their load directly underneath the body or behind the same, or so close to one side of the vehicle as to roll under the wheels. These are obvious disadvantages, since each load when so dumped is more or less in the path of the next vehicle and hinders the rapid and free movement of the same.

The principal object of my invention therefore is to eliminate the objectionable features of dumping bodies as above stated, by so constructing the body that the load when dumped will be thrown to one side clear of any possibility of fouling with the wheels.

Another object is to devise a dumping body which does not depend on any power actuated mechanism for its operation, but can be caused to dump to either one side or the other at the will of the operator, with no other instrument in his hands than any object capable of striking a fairly heavy blow, such as a hammer, wrench, iron bar or the like.

A third object is to devise a dumping body which does not require any lifting or pulling strain to cause it to operate and which is so evenly balanced on its supports as to be easily righted and positioned ready for another load by one man.

A further object of the invention is to produce a simple and inexpensive device and yet one which will be exceedingly effective for the purpose for which it is designed.

These objects I accomplish by means of such structure and relative arrangement of

parts as will fully appear by a perusal of the following specification and claims.

In the drawings similar characters of reference indicate corresponding parts in the several views.

Figure 1 is a perspective elevation of my improved dumping body showing the same mounted on a motor truck.

Fig. 2 is an end view of the same, showing the dumping position in dotted lines.

Fig. 3 is an enlarged fragmentary view of a locking catch.

Referring now more particularly to the characters of reference on the drawings, the numeral 1 denotes the longitudinal frame beams of the truck, provided with spaced pairs of transverse beams 2 thereon at suitable intervals. Positioned a certain distance above the beams 2 and in transverse and vertical alinement therewith are beams 3, on which are secured the floor planks 4 of the truck. End boards 5 are rigidly mounted on the floor, while overlapping and abutting against the end boards are side boards 6, the same height thereas.

Outside the side boards and secured thereto are vertical beams 7, extending downwardly outside and adjacent the beams 2 and 3, and pivoted to the latter in pairs, as shown at 8. These beams extend down to and normally rest on a common pipe or rod 9 projecting horizontally through all the beams 2 on each side. Of course, this may be a separate rod or pin for each pair of beams, if so desired. The lower ends of the beams 7, where they rest on the pipes or pins, are beveled transversely, as shown at 10. These ends and the outside of the beams adjacent thereto are sheathed with strap iron to better resist wear, as shown at 11.

Between each pair of beams 2 and 3 and pivoted thereto are arms 12, which while substantially vertical normally, diverge somewhat from each other toward their top ends and are positioned in symmetrical relation on each side of the vertical center line of the truck.

Spring straps 13 are secured to the end gates 5, and on each end have a latch 14 adapted to engage the outer sides of the side boards 6 at the top thereof. The straps of which the latches are a part are secured far enough back from the side boards as to allow the latches sufficient upward movement to clear the boards. The outer ends of the latch portions project outwardly to form lips 15,

adapted to receive the blow of a hammer or similar instrument thereunder to raise the latches.

The top edges of the side boards are preferably sheathed with continuous angle irons 16, in order to resist wear.

Similarly the inner surface of the side boards and the floor are covered with sheet metal or may themselves be made of pressed 10 steel or similar material. End cleats 17 are secured to the inner faces of the side boards beyond the end boards and lie adjacent to, so that these end members are prevented from any tendency to bulge outwardly when 15 the body is loaded.

The operation of the device is as follows, it being supposed that the load presumed to be in the body is to be dumped out the right hand side of the truck.

20 The driver merely strikes the lips 15 of the latches 14 an upward blow. This action releases the latches, and the weight of the load, acting both horizontally against the side boards and vertically on the beams 25 7 resting on the pipe 9, causes the side board on that side to move outwardly about the pivotal point 8 of the beams 7 as an axis, and at the same time causes the lower ends of said beams to move inwardly away 30 from engagement with the pipe. Since the function of the pipe is to support the beam, when this support is relatively removed, the arms 12 on that side will move downwardly toward the adjacent end of the beams, having already a slant in that direction, as 35 previously described, and thus allowing the floor to be tilted toward that side.

The angle of tilt is increased by reason of the action of the beams 12 on the other side, 40 which in their normal position have not passed a vertical center line, and hence with the movement away of the other beams 12, will cause the body to be raised somewhat at that point.

45 The downward slope of the side boards is limited by the abutting of the lower portions of the beams 7 against the under side of the floor 4. To prevent too great a space being had between the side boards and the 50 floor when in the dumping position, the latter projects beyond the side boards for a certain distance as at 18, being cut away at the points where the beams 7 lie. To limit the downward movement of the body as a 55 whole, a bumper 19 is provided on the under side of the floor on each side, and is adapted to strike on the top of the wheel 20 of the truck on that side. To raise the side board and position the body on a horizontal plane 60 for loading, a lifting force is exerted on the side board to raise the weight thereof. As soon as the beams 7 strike the pins 9, the beams then act as levers, and the entire body may then be raised until the side board is 65 in a vertical position, when the latches will

snap into position and hold the entire structure against undesired tilting.

It will be evident that while I have shown this body as being mounted on a motor truck chassis, its use or adaptation is not 70 confined to such vehicle, since the mechanism of the truck itself has nothing whatever to do with the dumping body structure. It may therefore be mounted on any 75 form of horse or power drawn vehicles, railroad cars, etc.

From the foregoing description it will be readily seen that I have produced such a device as substantially fulfills the objects of 80 the invention as set forth herein.

While this specification sets forth in detail the present and preferred construction of the device, still in practice such deviations from such detail may be resorted to as do not form a departure from the spirit of 85 the invention, as defined by the appended claims.

Having thus described my invention, what I claim as new and useful and desire to secure by Letters Patent is:—

1. A dumping body for vehicles comprising a floor portion flexibly mounted to the frame of the vehicle lengthwise thereof, rigid end boards on the floor, latches on the end boards, side boards adapted to rest in a vertical position adjacent the end boards and be held by the latches thereon, vertical beams secured to the side boards and pivoted to the floor, rods mounted in the frame of the vehicle longitudinally thereof and on which the beams normally rest, and means whereby when the latches on one side are released the potential energy of the load will cause the vertical beams on that side to move away from contact with the rods and the side board to swing outwardly to lie in a plane parallel to the floor and the latter to be simultaneously tilted at a downward angle on that side.

2. A dumping body for vehicles comprising a floor portion extending lengthwise of the vehicle, rigid end boards on the floor, latches on the end boards, side boards adapted to rest in a vertical position adjacent the end boards and be held by the latches thereon, vertical beams secured to the side boards and pivoted to the floor, rods mounted in the frame of the vehicle longitudinally thereof and on which the beams normally rest, and arms in transverse pairs positioned between the vertical beams, each such pair being pivoted both to the frame of the vehicle and the floor of the body and diverging from each other toward the top and arranged equi-distant from the vertical center line of the vehicle.

3. A dumping body for vehicles including a floor portion flexibly mounted to the frame of the vehicle lengthwise thereof, side boards pivotally secured to the floor, latches 130

to hold the same in a vertical position, means whereby when so positioned the floor portion will positively be held in a horizontal plane, and means whereby on releasing 5 the latches on either side board the potential energy of the load will cause that side board to assume a position in alinement

with the floor, and the latter to be simultaneously tilted down on that side.

In testimony whereof I affix my signature 10 in presence of a witness.

GEORGE G. NELSON.
